INDICATING INSTRUMENTS PROVIDED WITH A
MOVABLE IRON STRIP MEMBER

This invention relates to a moving iron-type instrument and more particularly to a moving iron-type instrument suitable for providing indications on a wide range scale.

As is well known in the art, the moving iron-type instrument comprises an exciting coil energized by an electric quantity such as current of a measured circuit. A movable shaft extending through the center of the coil, a fixed vane and a movable vane is so arranged as to form portions of a cylindrical surface concentric with the inner wall of the coil. Upon magnetization of the movable and fixed vanes by the exciting coil, a repulsive or attractive force is created between these vanes to cause them to repel and attract each other thus rotating the movable shaft which supports the movable vane.

Inasmuch as the instrument of this type responds to the first power of the voltage or current of an alternating current or direct current it is desirable that the relation between the current flowing through the exciting coil and the angle of deflection of the movable shaft or pointer should be linear. However, as the repulsive force or attractive force created in this type of instrument is proportional to the square of current it is not possible to establish the desired linear relationship between current and torque unless the configuration of the stationary vane secured to the spool of the exciting coil is designed to have a complicated shape.

While the operation of such an instrument is satisfactory for a scale covering 90°, for wider range scales covering 240°—270°, by the reasons enumerated below it is necessary to rely upon very troublesome measures to shape and work component parts, to securely fix the fixed and movable vanes, and to correct and adjust completed parts.

1. As the fixed vane for creating the repulsive force or attractive force is opposed to the movable vane which rotates about the movable shaft, it is necessary to form the fixed vane to have an exact cylindrical form concentric with the cylindrical surface described by the rotary movement of the movable vane.

2. Usually, the fixed vane is formed as a flat piece by stamping and then bent into the desired configuration such as cylindrical and the like configuration. However, it is very difficult to accurately bend the flat piece into the required configuration.

3. Further, it is necessary to arrange and secure the fixed and movable vanes in correct relative positions both in the longitudinal and transverse directions of the movable shaft.

Accordingly, one of the objects of this invention is to provide a moving iron-type instrument in which precision working and assembly of the movable vane as well as the stationary vane are easy.

Another object of this invention is to provide an improved moving iron-type instrument having a substantially uniform scale over a wide range, i.e. the spacing between scales for large deflection angles is substantially equal to that for moderate deflection angles.

These and other objects can be attained according to this invention by providing a moving iron-type instrument comprising an exciting coil adapted to be excited by the electric quantity to be measured, a movable vane arranged outside said exciting coil to be rotatable about the axis of said coil, and to be magnetized by said coil when it is energized, and a flat plate-type fixed vane having a required contour, said fixed vane being positioned outside said coil and between said coil and said movable vane in substantially parallel relationship with a plane described by the rotary movement of said movable vane to be magnetized by said coil when it is energized.

Upon energization of the coil by the measured electric quantity both movable vane and flat plate-shaped fixed vane are magnetized to an intensity corresponding to said measured quantity whereby to create a repulsive or attractive force between these vanes to rotate the movable vane. Accordingly,

a pointer mounted on the movable vane measures such electric quantities as voltage, current or power. The contour of the movable vane may be an elongated plate while that of the fixed vane may be a plate with an outer periphery gradually decreasing or increasing as hereinafter described in radius in the direction of rotation of the movable vane. As a result these vanes can be manufactured readily. Further, as these vanes are disposed outside the exciting coil they can be assembled readily and accurately.

10 Further, as the change in the angle of rotation of the moving vane is determined dependent upon the peripheral contour of the fixed vane it is possible to provide the desired wide range scale for the instrument by the proper selection of the peripheral contour of the fixed vane.

15 The foregoing objects and other objects as well as characteristic features of the invention will become more apparent and more readily understandable from the following description and the appended claims when read in conjunction with the accompanying drawings in which:

20 FIG. 1 shows a longitudinal section of a moving iron-type instrument embodying this invention;

FIG. 2 shows an enlarged longitudinal section of essential portions of the instrument shown in FIG. 1;

25 FIG. 3a shows a front view of the essential portions shown in FIG. 2;

FIG. 3b shows a front view of modified essential portions from those shown in FIG. 3a;

30 FIG. 4 shows a front view of modified essential portions from those shown in FIG. 3a;

FIG. 5 shows a front view of a scale board utilized in the instrument shown in FIGS. 1 to 3a;

FIG. 6 is a front view illustrating another example of the essential portions shown in FIG. 3a;

35 FIG. 7 is a front view to aid the understanding of the essential portions shown in FIG. 6;

FIGS. 8 and 9 show still further modifications of the essential portions shown in FIG. 4a;

40 FIG. 10 is a side view of the embodiment shown in FIG. 9 as viewed in the direction of an arrow;

FIGS. 11 and 12 illustrate perspective views of the movable vanes of different type;

FIG. 13 is a longitudinal sectional view of another embodiment of this invention;

45 FIGS. 14 through 18 show longitudinal sections of different modifications of the essential portions shown in FIG. 13;

FIG. 19 is a longitudinal sectional view of yet another embodiment of this invention;

FIGS. 20 and 21 show longitudinal sections of modifications of the essential portions shown in FIG. 19;

FIG. 22 is a longitudinal sectional view of a different embodiment of this invention including a pair of movable vanes and a pair of fixed vanes; and

50 FIGS. 23 and 24 are longitudinal sectional views illustrating modifications of the essential portions shown in FIG. 22.

Referring now to FIG. 1 of the accompanying drawings, the instrument shown therein includes a movable shaft 1 with its opposite ends journaled by bearings 2 and 3. A pointer 4 and a control spring 5 are secured to movable shaft 1. Further a movable vane 6 of soft iron is fixed to the movable shaft 1 in perpendicular to the axis thereof. The movable vane 6 is disposed outside an exciting coil 7 with said movable shaft extending through its center. The exciting coil 7 is supported by a frame 8 to which bearings 2 and 3 are secured. The frame 8 also supports a flat plate-shaped soft iron stationary vane 9 disposed between movable vane 6 and the exciting coil 7.

55 In the central portion of the fixed vane 9 there is provided a circular hole 9c of a suitable diameter for inserting the movable shaft therethrough. The periphery 9a of the fixed vane 9 is formed such that the radius thereof gradually decreases in the direction of the rotation of the movable vane 61 (in the direction shown by an arrow) or gradually increases in the direction of the rotation of the movable vane 62 (in the same direction as that of the movable vane 61 as shown in FIG. 3a)

as shown in FIG. 3b. As evident from FIGS. 3a and 3b, the fixed vane 9 having such a periphery as to gradually decrease in diameter in the direction of the rotation of the movable vane 61 or 62 and the fixed vane 9 having such a periphery as to gradually increase in diameter in the direction of the rotation thereof are entirely same in configuration to each other and can be used by selectively turning up the top or bottom side of the fixed vane as required. When the fixed vane 9 is used in such a position that the radius of the fixed vane gradually decreases in the direction of the rotation of the movable vane 61 as shown in FIG. 3a, use is made of such a movable vane that the starting end of the movable vane is selected as positioning near the maximum outer diameter portion of the fixed vane 9 and that the outer end 61a fixed at its inner end 61b to the movable shaft 1 substantially corresponds to the maximum outer diameter portion of the fixed vane 9.

Alternatively, when the fixed vane is used in such a position that the radius thereof gradually increases in the direction of the rotation of the movable vane 62, use can be made of such a movable vane that the starting end thereof is selected as positioning near the minimum outer diameter portion of the fixed vane and that the outer end 62a fixed at its inner end 62b to the movable shaft 1 substantially corresponds to the minimum outer diameter portion of the fixed vane. Therefore, energization of the exciting coil 7 will create a magnetic field between the fixed vane and the movable vane, causing the periphery 9a of the fixed vane 9 to be magnetized to either N or S pole.

Thus, if it is assumed now that the exciting coil 7 is energized by direct current or alternating current to produce magnetic flux around it in the direction shown by dotted line arrows in FIG. 2, the fixed vane 9 will be magnetized such that its outer periphery 9a becomes an N pole while its inner periphery 9b becomes an S pole. In the same manner, the movable vane 61 (62) will be magnetized to form an N pole at its outer end 61a (62a) an S pole at its inner end 61b (or 62b). Thus, a repulsive force will be created between the outer end 61a (62a) of the movable vane and outer periphery 9a of the fixed vane which are magnetized to the same polarity to rotate the movable vane 61 (62) in the clockwise direction to a point where the repulsive force and the resiliency of the control spring 5 balance each other.

The reason that the movable vane 61 (62) is driven in the clockwise direction can be explained as follows: As shown in FIG. 3a or FIG. 3b, the rotation locus 10 of the outer end 61a (62a) of the movable vane 61 (62) is a true circle about the shaft 1, whereas as the radius of the outer periphery 9a of the fixed vane gradually decreases (or increases) in the clockwise direction, the radial distance d , between the outer end 61a (or 62a) of the movable vane and the outer periphery 9a of the fixed vane increases gradually as the movable vane rotates in the clockwise direction. As this distance d increases, the repulsive force between the outer end 61a (62a) and the outer periphery 9a will decrease inversely proportional to the square of distance d . Thus it will be seen that by magnetizing the outer end 61a (62a) and the outer periphery 9a to the same polarity the movable vane 61 (62) will be driven in a direction in which the repulsion between the outer end 61a (62a) and outer periphery 9a decreases, or in the clockwise direction as viewed in FIG. 3a (or FIG. 3b). This relation can be expressed by mathematical equations as follows:

To obtain an uniform scale instrument over the full range of rotation of the movable vane 61 or 62, it is only required that there always be established the relationship expressed by the following equation:

$$iaKo \times \theta_A \quad (5)$$

Substituting the above equation (5) in the equation (4), there will result

$$d = Ko \sqrt{\theta_A} \quad (6)$$

Where:

Ko of equations (5) and (6) is a constant. If, therefore, the outer periphery 9a of the fixed vane 9 is so chosen as to satisfy the relationship represented by the equation (6), then it will

be apparent that there will be obtained a uniform scale instrument over the full range of rotation of the movable vane 61 or 62.

Expressed in terms of the radius r of the fixed vane 9, the relationship of the equation (6) above will run as follows:

$$In case of FIG. 3a r = r_{01} - K \sqrt{\theta_A} \quad (7)$$

$$In case of FIG. 3b r = r_{02} + K \sqrt{\theta_A} \quad (8)$$

Where:

10 r_{01} or r_{02} = radius of that part of the fixed vane 9 which faces the zero or rest position of the movable vane 61 or 62 when the coil 7 is deenergized. In case of FIG. 3a it represents a substantially maximum radius of the fixed vane 61 and in case of FIG. 3b a substantially minimum radius of the fixed vane 62.

15 K = constant.

To obtain the aforesaid uniform scale instrument, therefore, it is only required to define the outer periphery 9a of the fixed vane 9 so as to satisfy the relationship of the equation (7) or (8).

20 The foregoing is simply a theoretical discussion. In practice, therefore, necessary corrections should be made.

Further, where a magnetic body 20 of soft iron as shown by a dotted line in FIG. 5 is positioned near the portions of large 25 deflection angles 11a of the scale board 11, the magnetic body 20 will be magnetized to a polarity opposite to that of the outer end 61a of the movable vane when the exciting coil 7 is energized, whereby the movable vane 61 will be attracted against the repulsive force between said side 61c and discontinuous surface 9e, thus further increasing the scale spacings at the portion of large deflection angles 11a of the scale board 11. Said magnetic body 20 is formed threadable so that its level of height may be adjusted to control the intensity of said attractive force.

30 Further, a combination of said magnetic body 20 and the fixed vane 9 as shown by a dotted line in FIGS. 5 and 4 respectively may render the scale on the scale board 11 uniform.

As shown in FIG. 6, it is desirable to provide a suitable stop 35 19 at such a position that when the pointer 4 engages with the stop 19 the side surface 61d of the movable vane will be displaced clockwise by an angle θ_3 from the discontinuous surface 9e of the fixed vane.

With this arrangement as there is always a repulsive force 45 between the side surface 61d and the discontinuous surface 9e with the result that even when the pointer 4 is engaging with the stop 19 the movable vane 6 can rotate in the normal or clockwise direction.

As shown in FIG. 7, if the stop 19 were positioned such that the side surface 61d of the movable vane 6 would be displaced 50 by an angle θ_4 from the discontinuous surface 9e of the fixed vane in the counterclockwise direction, the movable vane 6 would be subjected to a torque in the counterclockwise direction due to the repulsive force created between the side surface 61d and the discontinuous surface 9e when the pointer 4 comes to engage with the stop 19, whereby the movable vane 6 will be continuously maintained at the position shown 55 in FIG. 7. For this reason it is desirable to locate the stop 19 at the position shown in FIG. 6 so as to ensure that the movable vane rotates in the desired direction when the instrument is energized. Such an object can also be attained by other suitable means that the provision of stop 19 as by bending the discontinuous surface 9e in a direction other than the radial direction.

60 65 Further as shown in FIG. 8, it is desirable to shape the outer contour 9a of the fixed vane 9 such that the radius r of a portion 9c of its outer periphery 9a facing to the movable vane 6 when the input to the exciting coil 7 is zero decreases rapidly.

With this construction even when the input to the exciting 70 coil 7 increases rapidly the movable vane can rotate in the normal or clockwise direction, thus preventing its reverse rotation.

Suppose now that the movable vane 6 is rotated and stopped at a point X by a certain input applied to the exciting coil 75 7.

If the input were increased gradually from zero, the movable vane 6 would rotate in the normal direction or in the clockwise direction and stop at the required point X. On the contrary, upon rapid increase of the input from zero, the movable vane 61 may rotate in the opposite direction by the shock of said rapid increase so that the pointer comes to collide against the stopper 19 and the movable vane cannot assume the desired position X. As reasons why such phenomenon occurs, the following factors will be considered. Namely, in the initial stage where the fixed and movable vanes have been magnetized by the magnetic field produced by the exciting coil, torques for rotating the pointer 4 in the clockwise direction or in the counterclockwise direction and produced in such a direction that the repulsive force between the outer periphery of the fixed vane and the outer end of the movable vane is gradually decreased due to the fact that the radial distance d between the outer periphery of the fixed vane and the rotation locus described by the outer end of a movable vane gradually increases in the desired direction of the rotation of the movable vane. However, the rotational torque caused by such repulsive force is not effectively acted upon with respect to the input such as the rapid increase of the input from zero, thus causing such phenomenon mentioned above to take place. However, when the radius of a portion 9c of the periphery of the fixed vane 9 is abruptly decreased as above described, the increment of d becomes larger when the movable vane 61 rotates in the clockwise direction than when the movable vane rotates in the counterclockwise direction. Thus, the movable vane 61 rotates in the direction in which d increases rapidly or in the direction in which the repulsive force decreases rapidly (clockwise direction).

Alternatively, it is also possible to assure rotation of the movable vane 61 in the correct direction by inclining a portion 9d of the fixed vane 9 towards the movable vane 61 near the stop 19, as shown in FIGS. 9 and 10.

It is to be understood that the shape of the movable vane 61 is not limited to an elongated strip as shown in the above described embodiments, but may be a sector in FIG. 11 of a rectangle 6c with an arcuate tip 6d as shown in FIG. 12.

As shown in FIG. 1, the frame 8 is supported on a base 13 through posts 12, which, in turn, is supported by a casing 14. The casing 14 has a cylindrical form with a glass cover 15 on its front end.

In FIG. 1, as the frame 8 is bulky and as the shaft 1 is extending through the center of the coil bobbin 18, the construction is relatively complicated and difficult to assemble precisely.

To avoid this difficulty, as shown in FIG. 13, it is advantageous to reduce the length of the shaft 1 so as to support the opposite ends of the shaft by bearings 2 and 3 in the frame 8 positioned outside the coil bobbin 18, said frame 8 being secured to base 13 through posts 12 and a supporting plate 21. Other portions in FIG. 13 are designated by the same reference numerals as in FIG. 1 to avoid repetition of their description.

FIGS. 14 through 18 show various modifications of this invention.

For the sake of description, modified portions along are showed in these FIGS. While in the embodiment shown in FIG. 13, the fixed vane 9 was shown as being interposed between the frame 8 and the supporting plate 21, in the modification shown in FIG. 14, the frame 8 is interposed between the fixed vane 9 and the supporting plate 21. Alternatively, as shown in FIG. 15, a central bore 18a of the bobbin 18 shown in FIG. 13 may be omitted or it may be a blind hole 18b as shown in FIG. 16. Further, as shown in FIG. 17 the supporting plate 21 may be omitted to connect the bobbin 18 and the base 13 directly or through posts 12. Alternatively, as shown in FIG. 18, a magnetic core 22 may be provided in the center of the bobbin 18 to cooperate with the fixed vane 9 or a coil casing 23 may be applied onto the outer surface of the bobbin 18 to cooperate with the core 22. By the construction shown in FIG. 18, the magnetic flux produced by the exciting coil 7 will be effectively directed toward the fixed vane 9.

FIGS. 19 through 21 show preferred constructions of mounting the fixed vane 9. In the arrangement shown in FIG. 19, the frame 8 is formed with a boss 8c snugly received in the central bore 9f of the fixed vane 9 to accommodate the fixed vane 9 in a recess 8d of the frame 8, whereby centers of the fixed vane 9, frame 8 and shaft 1 can be readily aligned.

In the arrangement shown in FIG. 20, the frame 8 is interposed between the supporting plate 21 and the fixed vane 9 which is supported by a clamping plate 24. Although in FIG. 19, the supporting plate 21 is secured to the base 13 through posts 12, the coil bobbin 18 and base 13 may be interconnected directly or through posts 12, without utilizing the supporting plate 21 as shown in FIG. 21.

Although in any of the above described embodiments, only one movable vane 6 and only one fixed vane 9 were used, as shown in FIG. 22 movable vanes 6 may be secured on the opposite ends of the shaft 1 to cooperate with independent fixed vanes 9, respectively.

With this construction the torque of the shaft 1 can be doubled.

FIGS. 23 and 24 illustrate modifications of essential portions shown in FIG. 22. In FIG. 23 a pipe 16 of soft iron is fit over the shaft 1 to magnetically couple two movable vanes 6, thus increasing the torque of the shaft 1, whereas in the arrangement shown in FIG. 24 a pipe 17 of soft iron for magnetically interconnecting fixed vanes 9 is shown as being fit to the inner surface of the coil bobbin 18.

While in the foregoing description the invention has been described with reference to preferred embodiments thereof, it will be obvious to those skilled in the art that various changes and modifications may be made therein without departure from the true spirit and scope of the invention as recited in the appended claims.

What we claim is:

1. A moving iron-type instrument, comprising:
  - a. a casing;
  - b. a cylindrical exciting coil secured to said casing and energized by an electrical quantity to be measured to produce a magnetic field around said coil;
  - c. at least one fixed flat plate vane lying in a first plane parallel to the end of the cylinder and being substantially circular, with the coil axis passing through the center;
  - d. at least one movable flat plate vane lying in a second plane parallel to the end of the cylinder outside said coil, comprising a radially extending member whose length is the same as at least one of the radii of the substantially circular fixed vane, and being so disposed as to locate said fixed vane between said movable vane and the end of said cylinder, set in a position corresponding to the radial portion of said fixed vane with said coil deenergized, and allowed to rotate about the axis of said coil and in a predetermined direction, when said movable and fixed vanes are magnetized by said magnetic field produced around said coil, due to the repulsive or attractive force created between said movable and fixed vanes, said fixed vane having a radially changing outer periphery such that the radial distance between the outer periphery of the fixed vane and the rotation locus defined by the outer end of said movable vane is gradually increased with respect to the predetermined direction in which said movable vane rotates;
  - e. support means including a shaft to rotatably support said movable vane and a restraining control spring to permit only a controlled rotation of said shaft, holding means to support said fixed vane; and,
  - f. an indicating means to indicate said measured electric quantity applied to said exciting coil by the extent of rotation of said movable vane.
2. A moving iron-type instrument according to claim 1 wherein the peripheral contour of said fixed vane is selected such that the radial distance d between the periphery thereof and the rotation locus described by the outer end of said movable vane gradually increases as said movable vane rotates in the normal direction and that said contour satisfies a relation

tion $d\alpha/\theta$ where θ represents the angle of the rotation of said fixed vane.

3. A moving iron-type instrument according to claim 2 wherein at least one magnetic piece is provided at a position where said movable vane comes to face said fixed vane when said movable vane rotates in the normal direction by the maximum angle.

4. A moving iron-type instrument according to claim 2 wherein the peripheral contour of said fixed vane is shaped such that the radial distance between the periphery of said fixed vane and the outer end of said movable vane is rapidly increased at the radius of a portion where said movable vane

faces said fixed vane when they are not magnetized.

5. A moving iron-type instrument according to claim 1 wherein only one movable vane and only one fixed vane are provided and wherein said movable vane is secured to a shaft extending through the center of said exciting coil on the one side thereof.

6. A moving iron-type instrument according to claim 1 wherein two movable vanes and two fixed vanes are provided and said movable vanes are secured to a shaft extending through the center of said exciting coil on the opposite sides thereof.
